OIL BURNER

John H. McIlvaine, Chicago, Ill., assignor to
McIlvaine Burner Corporation, Chicago, Ill., a
corporation of Illinois

Original application January 11, 1933, Serial No.
651,083. Divided and this application October
17, 1934, Serial No. 748,698

6 Claims. (Cl. 158—42.3)

This invention relates to liquid fuel or hydro-carbon burners, commonly known as oil burners, and, while the invention may be used for either industrial or domestic heating, the present application is for a furnace suitable for heating an average home.

In my Patent No. 1,654,658, I disclosed a burner in which the air and oil feed is increased or decreased in proper proportions by operation of a control valve and air shutter, either by a thermostatically controlled regulator or by a hand operated remote control unit. The burner of the present invention differs from that, generally speaking, in having a single gravity feed line with a main passage controlled by a solenoid valve which remains open so long as the current for the motor is not interrupted, and having a secondary passage controlled by a small valve adjusted to by-pass oil around the main valve while the current is interrupted, whereby to maintain a reduced flame sufficient to keep the house warm, until the normal feed and air blower draft is resumed.

The principal object of my invention is to provide a burner in which the fan housing is constructed to form a support for the other devices of the apparatus such as the regulator, float valve and control valve, in addition to supporting the outer end of the air tube that communicates with the housing. Then too, in accordance with my invention, a hollow supporting post is provided as one of the supports for the fan housing and is so disposed with respect to the float valve to serve as a housing or guide for the chain of the trip bucket forming a part of the trip mechanism for said valve, in addition to serving as a conduit for overflow oil from the overflow pipe of the float valve to conduct the oil to the trip bucket.

Still another object consists in providing a pair of spaced supports in connection with the aforesaid hollow supporting post whereby to give stability to the unit by a tripod support, although only two supporting posts are used, one at the front and the other at the rear of the unit. In accordance with the invention, the spaced supports also have a housing therebetween to enclose the trip bucket for protection thereof against accidental operation of the trip mechanism.

This application is a division of my application Serial No. 651,083, filed January 11, 1933.

The invention is hereinafter described by reference to the accompanying drawings, wherein—

Figure 1 is a side view of an oil burner made

in accordance with my invention, showing its application to a heater or furnace for a home;

Fig. 2 is an end view of the upper portion of Fig. 1;

Fig. 3 is a view looking at the other side of so much of the burner as appears in Fig. 2;

Fig. 4 is an enlarged vertical section on the line 4—4 of Fig. 2, and

Fig. 5 is an enlarged vertical section on the line 5—5 of Fig. 1.

The same reference numerals are applied to corresponding parts throughout the views.

In describing the burner of my invention, the liquid fuel will be referred to as oil. The oil circuit will be traced first. The oil is stored in a basement storage tank or underground storage tank outside. Where an underground tank is used, an automatic transfer pump is provided to bring the oil into the basement. The oil flows by gravity through the pipe 9 to the filter 10 which contains a large area of filtering cloth to remove all dirt and foreign matter, so that only clean oil is delivered to the burner. After passing through the filter, the oil enters the bottom of the housing of the float valve, indicated generally by the numeral 11, the purpose of which is to maintain a constant level of fuel, indicated by the line x—y in Figs. 2 and 4, so as to insure an even pressure of fuel and an even flame free from pulsations or surges. The oil flows from the float valve chamber by gravity through the pipe connection 12 to enter the housing of a solenoid valve, indicated generally by the numeral 13, which permits an unrestricted flow of oil so long as the current for the electric motor 14 is not interrupted. In other words, the solenoid valve is kept open by reason of energization of its coil by the same current for operating the motor. If the current is interrupted, a main valve in the solenoid valve 13 is closed and the oil is by-passed through a secondary valve therein, adjusted to reduce the flow to approximately one-third of the maximum capacity of the burner, so as to maintain a reduced flame using natural draft and sufficient to keep the house warm until the normal feed and air blower draft is resumed.

The oil is discharged from the solenoid valve 13 through neck 15 of the control valve, indicated generally by the numeral 16. The adjustment of valve 16 regulates the oil feed according to the heat demand. From this valve the oil flows by gravity through pipe 17 and connection 18 to the pipe 19, which extends lengthwise inside the air tube 20, to the elbow 21 disposed over the firepot 22. The elbow 21 is a one-piece casting constructed with a slight offset

therein so as to define an overflow point 23 therein below an air opening 24, the purpose of which is to prevent siphoning. The opening also faces in the proper direction with relation to the air flow through the tube 20 so as to have the benefit of the air pressure to assure positive feeding of the oil downwardly through the elbow 21, as well as assist in breaking up the oil into small particles at the sharp delivery point 25 and improve combustion, especially at high loads. A screw 26 serves to support the elbow 21 in the tube 20 to insure a definite relationship between the point 25 and the point in the firepot 22 toward which the fine stream of oil is to be discharged. Reference may be had to my Patent 1,654,659 for an understanding of the construction and mode of operation of the firepot 22. It is clear then from the foregoing description that the oil burner of my invention has a simple gravity feed, regulated in accordance with heat demand by the valve 16, and controlled by the solenoid valve 13 to change from a normal oil feed while the motor is running to furnish a forced air draft, to a restricted feed for a low "carry over" flame when the current for the motor is interrupted by reason of a temporary shut-down of the electric service for the home.

The air for mixture with the vaporized fuel and to support combustion is supplied by a centrifugal fan 27 operating in a housing 28, which has a tangential discharge neck 29 communicating with the outer end of the air tube 20, whereby to deliver the air through the tube into the firepot 22, where the mixing of air and oil and its combustion occurs. The shaft indicated at 30 in Fig. 4 is the armature shaft of the motor 14 which extends into the housing 28 and has the fan rotor fixed thereon. The amount of air delivered by the fan is regulated by the rotatably adjustable shutter plate 31. This shutter plate, in accordance with my Patent 1,654,658, is mounted for rotation about the center 32 relative to a stationary shutter plate 33 removably secured, as by screws, on the housing 28. Removal of the shutter plate 33 affords access to the inside of the blower housing 28 for cleaning out dirt that may collect therein especially at the neck 29 discharging into the tube 20. The fixed plate 33 has two diametrically opposed quadrants with relation to which the diametrically opposed quadrants of openings 34 and 35 in the plate 31 are arranged to register. The openings 34-35 all have closure plates 36 thereon adjusted so that only the proper amount of air is allowed to enter at each one of a succession of adjusted positions of the plate 31, the plate being turned one step at a time and adjustments of the closure plates being made one at a time so as to secure the exact amount of air delivery for each position of the plate. A link 37 provides connection between the shutter plate 31 and a lever arm 38 fixed to the hand wheel 39 of the control valve 16, so that the control valve is opened wider and wider at each step toward wider and wider opening of the shutter. Another link 40 provides connection between the shutter plate 31 and the rotatable crank arm 41 of the regulator 42, that is, where automatic control is desired; in some installations, a remote control unit is provided having connection with the shutter plate for direct manual adjustment thereof. In the automatic control, the room thermostat located conveniently upstairs causes the regulator 42 to operate so as to adjust the size of the flame and constantly balance the heat loss of the building and thus maintain a very even temperature.

In the event the flame is accidentally extinguished, oil runs out of the firepot 22 into the base 43 constructed to serve as a catch basin. A pipe 44 drains the oil from the base 43 into a trip bucket 45, whereby to place a load on the trip lever 46, to which the bucket is connected by the chain 47. The trip mechanism is similar to that disclosed in my Patent 1,692,046 and embodies a drop weight 48 pivoted as at 49 and normally disposed on one side of dead center in a raised 10 cocked position, but arranged when the lever 46 is moved downwardly under load of the trip bucket in filling, to be moved over dead center so as to drop onto the lever 46 with a hammer-like blow. The lever 46 is disposed over the projecting end 50 15 of the needle valve, or other equivalent element in the float chamber, and serves to depress the same and shut off communication between the oil supply pipe 9 and the float chamber, so that no further oil will be delivered. The trip bucket 45 is also 20 arranged to catch oil draining from the float valve 11 through an overflow tube 51. The latter communicates with the float chamber at a point just below the cover 52 thereof and well above the normal level, indicated by the line x-y. Thus, if 25 the oil level rises in the float valve through a failure of the float mechanism to close the needle valve, overflow oil is drained through the tube 51 and into the trip bucket 45, whereby to cause the trip mechanism to close the needle valve 30 similarly as stated before. In passing, I would call attention to the tube 52 connecting the neck 15 of the valve 16 with the float chamber 11, at a point above the oil level x-y, by connection with the tube 51 next to the float chamber as shown. 35 This is simply to permit venting air from the oil line ahead of the valve 16, so that no air bubbles will occur in the oil fed through pipe 19 to the firepot and disturb the evenness or continuity of the stream of oil dropping from the point 25. 40

Referring now to Figs. 1 to 4, mainly Fig. 4, attention is called to the fact that the housing 28 is cast in one piece with a downwardly projecting boss 53 and a rearwardly projecting boss 54 for support of the housing on standards or posts 55 45 and 56, respectively. The post 55 telescopes in a tubular base 57 secured, as indicated, to the floor, and a set screw 58 is provided to fasten the post 55 in place when the housing 28 is disposed at the desired elevation. A pair of spaced supports 59 50 constitute a base for the post 55, a cast yoke 60, to which the lower end of the post 56 is secured, being slidable up and down on the supports 59 and arranged to be secured in adjusted position by means of set screws 61. The supports 55 59 are suitably secured to the floor as indicated. These two supports together with the base 57 constitute a tripod support for the housing 28, although only two posts 55 and 56 are utilized. The structure, therefore, has the desired stability. The housing 28, it will now be seen, has other integral projections and is otherwise so constructed for support of the regulator 42, float valve 11, control valve 16, and motor 14, in addition, of course, to those parts which by reason of their 60 connection with the parts named, are supported thereby, as, for example, the air tube 20, the outer end of which is connected with the housing 28 in the neck 29. A bracket 62 and boss 63 formed integral with the housing 28 on its periphery support the regulator 42. A bracket 64 formed integral with the housing 28 also on its periphery supports the float valve 11, as well as its associated trip members, and a shield 65 therefor. A small projection 66 is formed integral with the bracket 70 75

64 and constitutes a support for the trip mechanism. Another lug 67 formed integral with the bottom of the housing constitutes a support for the control valve 16 and also in a measure for the 5 solenoid valve 13, the latter being connected with the valve 16 as well as with the float valve 11. The housing of motor 14 has a flange 68 by means of which it is bolted directly to the side of the housing 28, as at 69, so as to be supported by the 10 housing.

The supporting post 56 is so disposed with respect to the float valve 11 and its associated trip mechanism that the chain 47 extending from the trip lever 46 can be extended downwardly through the post 56 to the trip bucket 45, the latter being disposed inside a sheet metal housing 70 provided therefor in the yoke 60. Thus, the chain 47 is protected for the greater portion of its length from accidentally being brushed against and causing 15 the operation of the trip mechanism, and the trip bucket is also protected against accidental engagement such as might result in the functioning of the trip mechanism. These parts are also kept out of sight so that children or others will not be 20 apt to tamper with them and throw the burner out of operation. A hinged door 71 is provided on the front of the housing 70 to afford access to the trip bucket whenever it may be necessary to empty it. The post 56, besides serving as a 25 housing and guide for the chain 47 of the trip bucket, also has the lower end of the overflow tube 51 extended into it so as to conduct overflow oil from the float valve to the trip bucket. The post 56, therefore, has a three-fold function; besides 30 serving as a support for the housing 28 and its appurtenances, it serves these other two purposes. The pipe 44 for draining oil overflowing from the firepot 22 into the base 43 has connection with the yoke 60, as indicated in Fig. 5, and a passage 35 72 is provided in the yoke communicating with the end of the pipe 44 and arranged to discharge into the trip bucket 45.

It is believed the foregoing description conveys a good understanding of the objects and advantages of my invention. While I have made 45 reference to various specific details of construction found in this single working embodiment of my invention, it should be understood that the invention is not limited thereto but embraces 50 all legitimate modifications and adaptations coming within the spirit and scope of the appended claims.

I claim:

1. In combination with a liquid fuel burner and 55 an apparatus for feeding fuel and air under pressure thereto; a combined overflow cut-off and supporting structure for said apparatus comprising a front upright supporting post vertically adjustable on a fixed base, a hollow rear upright 60 supporting post vertically adjustable on a second fixed base including a pair of laterally spaced fixed supports, a housing supporting said rear post disposed between and adjustable vertically on said spaced supports, an overflow fuel receptacle enclosed in said housing, a float controlled fuel valve and a trip mechanism therefor operative to close said valve to shut off fuel feed, both being positioned above said hollow post, means extending through said post and connecting said 65 receptacle with said trip mechanism, and means including said hollow post and housing for conducting overflow and unconsumed fuel into said receptacle.

2. An apparatus as set forth in claim 1 wherein in said overflow conducting means includes a conduit extending from the float chamber for said valve at a point above the normal level of the fuel therein into the upper end of said supporting post, and a vent for the fuel line at a point intermediate said valve and burner comprising a conduit which communicates with said first conduit. 5

3. In combination with a liquid fuel burner and an apparatus for feeding fuel and air under pressure thereto; a supporting structure for said apparatus comprising a hollow upright supporting post vertically adjustable on a fixed base including a pair of laterally spaced fixed supports, and a housing supporting said post disposed between and adjustable vertically on said spaced supports, and an overflow cut-off combined with said supporting structure comprising an overflow fuel receptacle enclosed in said housing, a float controlled fuel valve and a trip mechanism therefor operative to close said valve to shut off fuel feed, both being positioned above said hollow post, means extending through said post and connecting said receptacle with said trip mechanism, and means including said hollow post for conducting overflow fuel into said receptacle. 10 15 20 25

4. In combination with a liquid fuel burner and an apparatus for feeding fuel and air under pressure thereto; a supporting structure for said apparatus comprising a hollow upright supporting post vertically adjustable on a fixed base including a pair of laterally spaced fixed supports, and a housing supporting said post disposed between and adjustable vertically on said spaced supports, and a fuel feed cut-off combined with said supporting structure comprising a fuel receptacle enclosed in said housing, a fuel valve and a trip mechanism therefor operative to close said valve to shut off fuel feed, the trip mechanism being positioned above the hollow post, means extending through said post from the trip mechanism to the fuel receptacle for suspension of the latter on the former, and means for conducting unconsumed fuel into said receptacle. 30 35 40 45

5. In combination with a liquid fuel burner and an apparatus for feeding fuel and air under pressure thereto, including a blower housing; a supporting structure for said apparatus comprising a second housing below the blower housing, 50 a hollow vertical support rigidly interconnecting said housings, and means whereon the lower housing is vertically adjustable, and a fuel cut-off combined with said supporting structure comprising a fuel receptacle enclosed in said lower housing a float-controlled fuel valve and a trip mechanism therefor operative to close said valve to shut off fuel feed, both being positioned above the hollow support, means extending through said hollow support and connecting said receptacle 55 60 with said trip mechanism, and means including said hollow support for conducting overflow fuel into said receptacle.

6. An apparatus as set forth in claim 5 wherein the float-controlled fuel valve includes a float 65 chamber having an atmospheric space above the normal level of the fuel therein, and a vent for the fuel line at a point intermediate said valve and burner comprising a conduit communicating with said space. 70
